UNITED STATES PATENT OFFICE.

JOHN J. METZ, OF MEADVILLE, PENNSYLVANIA.

TRAIN-ORDER HOLDER AND DELIVERER.

No. 895,282.

Specification of Letters Patent.

Patented Aug. 4, 1908.

Application filed May 29, 1908. Serial No. 435,697.

To all whom it may concern:

Be it known that I, JOHN J. METZ, a citizen of the United States, residing at Meadville, in the county of Crawford and State of Pennsylvania, have invented new and useful Improvements in Train - Order Holders and Deliverers, of which the following is a specification.

My invention pertains to train-order holders and deliverers; and it contemplates the provision of a device of the kind stated which is simple and inexpensive in construction and yet entirely practical and possessed of many material advantages.

15 The invention will be fully understood from the following description and claims when the same are read in connection with the drawings, accompanying and forming part of this specification, in which:

20 Figure 1 is an elevation of a train-order holder and deliverer constructed in accordance with my invention. Fig. 2 is an enlarged detail section taken in the plane indicated by the line 2—2 of Fig. 1 and illustrating the relative arrangement of the outer and inner rings and the covering of the device. Fig. 3 is a detail view illustrative of the manner in which a train-order is drawn into one of the pockets afforded at the ends 30 of said covering. Fig. 4 is a detail view taken at a right angle to Fig. 1 and illustrating the bifurcation in the handle. Fig. 5 is a view of a modification hereinafter referred to in detail.

35 Referring by letter to the said drawings and more particularly to Figs. 1 to 4 thereof: A is the outer ring of my novel device, which is preferably made of resilient steel wire.

B is the inner ring which is preferably made 40 of comparatively light wire.

C is a covering which is preferably in the form of a tube and is open at its ends for an important purpose hereinafter set forth, and D is a connection, preferably a link of wire 45 having hooked ends a, through the medium of which the ends of the covering C are connected, and the covering is held taut on the rings A and B. The covering C may be made of any material consonant with the 50 purpose of my invention without involving departure from the invention as claimed, though I prefer to form it of flexible canvas,

and I also prefer to dip it into boiled or hard oil, this latter in order to render it dirt and water proof. I also prefer to paint the covering or otherwise render the same light in color so that the same can be readily seen at night as well as in the daytime.

It will be readily understood from the foregoing that the rings A and B in combination with the soft covering C drawn taut and fastened in such state on the rings, form an open device which is light in weight, flexible and soft, and is therefore not liable to injure an engineer or fireman on a fast moving train 60 when he passes his arm through said device with a view of taking the order holder and deliverer from a person standing at the side of the railway. It will also be noted that the said device is well adapted to withstand the 65 rough usage to which devices of corresponding character are ordinarily subjected, and that because of said device being flat, see Fig. 2, a lamp or lantern held at the side of the device toward an approaching train will illuminate the device so that the same may be 70 readily seen in a dark night by the engineer of the train.

The ends of the covering C being open are adapted to receive messages to be placed on 80 moving trains and are also adapted to protect messages against the weather and against being torn or otherwise injured. Messages may be tucked or otherwise placed in the said pockets without involving departure from the spirit of my invention, though I prefer to employ message carriers 85 for the purpose. The message carrier shown in Figs. 1 and 3 is employed in combination with the lower pocket of Fig. 1, but it will be 90 understood that when deemed expedient a similar carrier may, in the discretion of the manufacturer, be employed in combination with the upper pocket of Fig. 1. The message carrier illustrated comprises an open 95 loop E, a tongue F, of thin metal, connected to one end of the said loop, and a handle or finger-piece G connected to the other end of the loop E and extending through an aperture in the covering C and terminating in an 100 eye or other suitable enlargement. In using the said carrier to place a message in its complementary pocket, the message is arranged with the bight of its fold in the loop E and

with its end portion resting at opposite sides of the tongue F, and the operator then grasps the enlargement of the handle G and pulls the loop E into the covering C until the message is entirely inclosed and hidden from view by the said covering. It will also be manifest that when it is desired to remove the message from the pocket in the covering C, the same may be readily accomplished by 10 the engineer introducing his thumb and fore finger in the end of the pocket and grasping both the message and the tongue F, and in this connection it will be noted that incidental to the withdrawal of the message the tongue F will prevent the imposition of strain on the message and in that way will preclude tearing of the message.

H is a stem having a flat portion b fixed to the ring A, and I is a handle which is preferably, though not necessarily, equipped with a spring-pressed clamping device J adapted to be used in an emergency to clamp a message against the handle in the manner shown in Fig. 1. The said handle I is also provided 25 with a socket d and a bifurcation e; the said socket d being designed to receive the stem H, and the bifurcation e having for its office to receive the flat portion b of the stem. When the handle I is permanently connected 30 with the open device the connection is effected through the medium of a pin c extending transversely through the handle and the flat stem portion b. I would have it understood, however, that my invention comprehends 35 connecting the handle I and the open device in a detachable manner so that a person standing at the side of a railway may retain the handle I in his hand while the open device is taken on a moving train by the engineer thereof, and when this latter scheme is 40 desirable it is simply necessary to omit the said pin c, since when this is done the stem H of the open device may be readily withdrawn from its socket in the handle I.

45 When deemed expedient a clamping device like the device J or of any other suitable type may be employed at a suitable point on the outside of the covering C, but this clamping device is not illustrated, inasmuch as it 50 may be employed or omitted at the pleasure of the manufacturer without affecting my invention.

In the embodiment of my invention illustrated in Fig. 5, the handle I² which is similar 55 to the handle I of Figs. 1 and 4, is detachable from the stem H² and the flat portion b² thereof, and is designed when detached to be placed in the position shown diametrically across the open device and with its bifurcation e receiving the inner ring B of said device, this in order to render the message holder and deliverer compact and permit of it being 60 readily carried. The said handle I² of the modified message holder and deliverer is

connected through a chain K with the outer ring A, and hence it will be manifest that when it is desired to use the construction shown in Fig. 5, the handle I² may be disengaged from the inner ring B and placed in engagement with the stem H² and employed 70 to facilitate the delivery of the construction as a whole to the engineer or fireman of a moving train.

The constructions herein illustrated and described constitute the preferred practical 75 embodiments of my invention, but it is obvious that in the future practice of the invention such changes in the form, construction and relative arrangement of parts may be made as fairly fall within the scope of the 80 claims hereto appended.

Having described my invention, what I claim and desire to secure by Letters-Patent, is:

1. A train-order holder and deliverer having an open device made up of a suitable frame, and a soft covering arranged on the said frame.

2. A train-order holder and deliverer having an open device made up of inner and outer rings, forming a frame, and a soft covering arranged on the frame formed by the said rings.

3. A train-order holder and deliverer having an open device in which is a pocket closed 95 at its sides and open at its end and designed to receive and hold a message.

4. A train-order holder and deliverer having an open device in which is a pocket designed to receive and hold a message, and 100 also having a carrier for facilitating the placing of a message in said pocket.

5. A train-order holder and deliverer having an open device made up of a suitable frame, and a soft covering arranged on the 105 said frame and having a pocket designed to receive and hold a message.

6. A train-order holder and deliverer having an open device made up of a suitable frame, and a soft covering arranged on the 110 said frame and surrounding the same transversely and provided with an open end, whereby its end portion forms a pocket adapted to receive and hold a message.

7. A train-order holder and deliverer having an open device comprising inner and outer rings forming a frame, and a soft covering arranged on the frame formed by the rings and surrounding said frame transversely and open at one end, whereby its end portion forms a pocket adapted to receive and hold a message.

8. A train-order holder and deliverer comprising an open device made up of inner and outer rings forming a frame, a soft covering 125 arranged on the frame formed by the rings and surrounding said frame transversely and open at one end, whereby its end portion

forms a pocket adapted to receive and hold a message, and a carrier connected with and movable with respect to the said covering and adapted to facilitate the placing of a message in said pocket.

9. A train-order holder and deliverer comprising an open device made up of inner and outer rings forming a frame, a soft covering, of tubular form, arranged on said frame and surrounding the same transversely, and a connection intermediate the ends of the said covering for holding the same taut on the rings forming the frame.

10. A train-order holder and deliverer comprising an open device made up of a frame, and a soft covering, of tubular form, arranged on said frame and having its ends connected together.

11. A train-order holder and deliverer comprising an open device made up of inner and outer rings forming a frame, a soft covering, of tubular form, arranged on said frame and surrounding the same transversely, and a link interposed between and having 25 hooks at its ends engaged with the ends of said covering.

12. A train-order holder and deliverer comprising an open device made up of inner and outer rings forming a frame, a soft covering, of tubular form, arranged on said frame and surrounding the same transversely and having an open end adapted for the insertion in the covering of a message, and a link interposed between and having hooks at its 35 ends engaged with the ends of said covering and adapted to hold the covering taut on the frame.

13. A train-order holder and deliverer comprising an open device made up of a frame and a covering thereon and having flat sides, for the purpose set forth.

14. A train-order holder and deliverer comprising an open device having a pocket, and means extending through a wall of the 45 pocket for drawing a message into the pocket.

15. A train-order holder and deliverer comprising an open device having a pocket, a loop adapted to receive a message, means extending through a wall of the pocket and 50 connected with said loop, and means connected with and extending outward from the pocket for facilitating the withdrawal of a message therefrom.

16. In a train-order holder and deliverer, the combination of a pocket, and means through the medium of which a message 55 may be drawn into said pocket.

17. In a train-order holder and deliverer, the combination of a pocket, and means extending through a wall of the pocket and adapted to carry a message, whereby the message may be readily drawn into the 60 pocket.

18. In a train-order holder and deliverer,

the combination of a pocket, means movable 65 with respect to the pocket and adapted to receive a message, and means connected with the first named means and extending through a wall of the pocket, for the purpose set forth.

19. In a train-order holder and deliverer, the combination of a pocket, means movable with respect to the pocket and adapted to receive a message, means connected with the first named means and extending through 75 a wall of the pocket, and means extending outward from the first named means and adapted to permit of the withdrawal of a message without the imposition of strain on the same.

20. In a train-order holder and deliverer, the combination of a pocket having an aperture in one of its walls, an open loop movable with respect to the pocket, a handle connected to said loop and extending through 85 the aperture in the wall of the pocket, and a tongue connected to and extending outwardly from the loop.

21. In a train-order holder and deliverer, the combination with an open device comprising inner and outer rings forming a frame, and a soft covering arranged on said frame, and a stem having a flat portion fixed with respect to and extending outward from the outer ring of the frame; of a handle 95 having a socket to receive the stem and a bifurcation to receive the said flat portion of the stem.

22. In a train-order holder and deliverer, the combination with an open device comprising inner and outer rings forming a frame, a soft covering arranged on said frame, and a stem having a flat portion fixed with respect to and extending outward from the outer ring of the frame; of a handle having 100 a socket receiving the stem and a bifurcation receiving the flat portion of the stem, and a connection extending through the handle and the flat portion of the stem.

23. A train-order holder and deliverer 110 comprising an open device made up of a resilient frame, and a soft covering thereon.

24. In a train-order holder and deliverer, the combination with an open device comprising inner and outer rings forming a 115 frame, a soft covering arranged on said frame, and a stem having a flat portion fixed with respect to and extending outward from the outer ring of the frame; of a handle having a socket to receive the stem and a bifurcation 120 to receive the said flat portion of the stem, and a flexible connection permanently attaching the handle to the open device and adapted to enable the handle in one position to receive in its bifurcation the inner ring of 125 the frame and in another position to receive the stem and the flat portion thereof.

25. In a train-order holder and deliverer,

the combination with an open device, of a handle, and a permanent flexible connection intermediate the open device and the handle, said handle being adapted in one position to extend across the open device and in another position to extend outwardly from the open device and hold the same.

In testimony whereof I have hereunto set my hand in presence of two subscribing witnesses.

JOHN J. METZ.
